Inventor:

Robert E. Lewis,
By H. C. Henderson,
Attorney.

UNITED STATES PATENT OFFICE.

ROBERT EMMETT LEWIS, OF MOULTRIE, GEORGIA.

REINFORCED-CEMENT FENCE-POST AND ANCHOR-BLOCK FOR WIRE FENCES.

1,265,460.

Specification of Letters Patent.

Patented May 7, 1918.

Application filed November 27, 1916. Serial No. 133,664.

To all whom it may concern:

Be it known that I, ROBERT EMMETT LEWIS, a citizen of the United States, residing at Moultrie, in the county of Colquitt 5 and State of Georgia, have invented a new and useful Reinforced-Cement Fence-Post and Anchor-Block for Wire Fences, of which the following is a specification.

My invention relates to fence posts. It 10 has for its object to provide a construction in which the wire fencing may be quickly attached to the post and securely fastened thereto at the top and bottom by the upper and lower strands engaging in grooves or 15 ways formed so as to readily receive and prevent accidental disengagement of the strands interlocking with the post at the grooves, and in a manner that will tend to prevent vertical and also longitudinal movement 20 of the wire constituting the fencing.

To the accomplishment of the foregoing and such other objects as may hereinafter appear the invention consists in the features hereinafter particularly described and 25 then sought to be clearly defined by the claims, reference being had to the accompanying drawing forming a part thereof, and in which

Figure 1 is a perspective view of a post 30 embodying the invention, and showing portion of a wire fencing attached;

Fig. 2 is a side view of the upper portion of the post, and showing the manner of attaching a top strand of wire if desired;

Fig. 3 is a plan view of Fig. 2;

Fig. 4 is a front view of Fig. 2;

Fig. 5 is a rear view of Fig. 2;

Fig. 6 is a plan view of the base of the post with the post in section;

Fig. 7 is a side view of the base with post omitted;

Fig. 8 is a plan view of Fig. 7;

Fig. 9 an end view of Fig. 7;

Fig. 10 is a perspective of an anchor that 45 may be used for attaching a supplemental strand at the top of the post

In the drawing the numeral 1 designates a base member designed to be set into the ground and have the lower part of the fencing 50 attached thereto; and 2 the upright or post which is formed with an overhanging head or cap 3. The base member, post and cap will preferably be molded or formed of concrete or cement, and the post may have 55 reinforcing rods and strands 4 molded therein. The base member 1 has formed

in it, near the lower end of the post, a horizontally extending slot or groove 5 which is intersected by a slot or groove 6 extending obliquely across the groove 5 and 60 whereby is formed an overhanging wall to the top of the slot or groove 5, preferably at or toward opposite ends of the groove, as illustrated. Under this construction the lower strand of the fencing is introduced 65 through the obliquely extending slot or groove and when it enters the slot 5 it assumes its normal position parallel with the slot 5 and under the overhanging top wall of the slot so that it is prevented from 70 moving upward out of the slot. In the head 3 there is formed a slot 7 extending through from side to side and which is intersected by a slot 8 extending from the face of the head rearwardly so that the top strand of 75 the fencing may be introduced into the slot 7 through the slot 8 and thus the fencing will be supported at the top by the head. The cap or overhanging portion of the head is formed with a vertically extending 80 slot 9 designed to receive the upper portion of one of the vertical strands of the fencing which will lie against the face of the upright or post 2 and to which it may be fastened by staples 10, if so desired. By 85 having the upper portion of one of the vertical strands fit in the vertical slot of the cap or head, the fencing will be held against movement in the direction of its length. The formation of the slots at the 90 base and top of the post securely hold the fencing against vertical movement and the vertical slot in the face of the cap holds it against longitudinal movement, and the attachment of the fencing is easily and 95 expediently made. At times it is desirable to secure the bottom of the fencing at a point between the posts to afford firmness to the fencing and for that purpose a base member formed as previously described but 100 with the upright or post omitted, such a member being illustrated in Fig. 7 of the drawing.

At times it may be desired to provide at the top of the fencing an additional strand 105 of the barbed type as indicated by the numeral 11. In that event the head or cap of the post is recessed at 17 to receive an anchor member 12 having a notched arm 13 to receive the barbed strand and at the 110 other end formed with a heel extension 14 to receive a wire loop 15 secured to the post

by a staple 16 so as to hold the anchor in the recess against the tension exerted by the barbed wire. The portion of the anchor member 12 which lies in the slot of the post 5 head which receives the top strand of the fencing is formed with a spur or notch 18 to receive the upper strand of the fencing so that the fencing will serve to prevent the notched arm 13 of the anchor from being 10 forced upward out of place, the fencing being held to its place by the walls of the slots through which its upper and lower strands pass.

Having described the invention, what I 15 claim is:

1. In a fence, a base member formed with a slot to receive a strand of the fencing, a post rising from the base member and formed with an overhanging head, said

head having a rearwardly and downwardly 20 extending slot to receive a horizontal strand of the fencing and the face of the overhanging head formed with a vertical slot to receive a vertical strand of the fencing to permit the fencing to lie relatively close to 25 the face of the post.

2. In a fence, a post formed with a base member and a head member, the base and head members each formed with slots for receiving, respectively, upper and lower 30 strands of the fencing, and an anchor member affixed to the head member of the post to receive a supplemental wire strand, said anchor being formed with a notch within the strand receiving slot in the post head to 35 receive the top strand of the fencing.

ROBERT EMMETT LEWIS.

Copies of this patent may be obtained for five cents each, by addressing the "Commissioner of Patents, Washington, D. C."
